UNITED STATES PATENT OFFICE.

ALEXANDER ROY DAVIDSON, OF EDMONTON, ALBERTA, CANADA.

PHONOGRAPH-RECORD-ROTATING MECHANISM.

Application filed March 17, 1926, Serial No. 95,404, and in Canada February 24, 1926.

My present invention appertains generally to improvements in the art of sound reproducing instrumentalities, and specifically to phonograph record rotating mechanism providing accelerating rotation and uniform speed of travel of the record sound groove past the tone arm stylus, as described in the present specification and illustrated in the accompanying drawings.

10 In phonographs and sound reproducing instruments of this character, the playing disc record is rotated at a uniform speed. Therefore, as a record is played, the speed of travel of the disc record sound groove past the tone arm gradually decreases, in consequence of which the number of notes which may be played from a record is very limited.

20 To obviate this, I propose, in the manufacturing of the records, to rotate the same so as to provide a uniform speed of travel of the sound groove past the said stylus, and in the playing of the record on the sound reproducing instrument, to gradually accelerate the playing record to provide uniform speed of travel of the sound groove past the reproducing tone arm stylus, to harmonize with the record. By doing this, the volume of notes which may be played from a record 30 will be greatly increased, in that, when the record is being produced and played, and the stylus is seated in a sound groove near the periphery of the record, the record is rotated at the required speed to make and play the notes. As the spiral sound grooves become smaller in diameter, this speed of rotation of the record is proportionately increased to provide a uniform speed of travel of the said groove past the stylus.

40 This invention has to do particularly with the reproducing instrument for playing records manufactured as above noted, and has for its object the provision of reproducing mechanism comprising, in combination with record rotating means and a tone arm, of means interconnecting the same, so that when a record is being played and the tone arm moves thereacross, the speed governing means is released to increase the speed of rotation of the record in unison, thus providing a uniform speed of travel of the sound groove past the tone arm stylus throughout the playing period of the record.

45 The invention is further characterized by the provision of means for adjusting said interconnecting means to vary the playing

speed of the instrument as occasion demands.

With the foregoing and other objects in view which will appear more fully as the description proceeds, the invention resides 50 in the novel combination and arrangement of co-operating elements as hereinafter more specifically set forth, claimed and shown in the accompanying drawings forming a part of the present application, and in which:

Fig. 1 is a fragmentary transverse vertical section of the upper portion of a phonograph, illustrating the application of my invention.

Fig. 2 is a fragmentary detail view, showing the phonograph governor and speed control, and

Fig. 3 is a similar view showing the governor and speed control in another position.

Like numerals of reference designate corresponding components throughout the several views.

The numeral 4 designates the cabinet of a phonograph in general, which is provided with the usual detachable cover section 5. 50 A tone arm 6, carrying the sound reproducing box 7 and stylus 8, is pivoted, in the usual manner to the base plate 9. 10 designates the sound box. The record plate driving mechanism may, for illustration purposes, comprise the spring motor designated at 11 in its entirety, which drives the record plate rotating spiral gear 12, the speed of which is controlled by the conventional governor 13.

90 My invention resides in the interconnecting of the tone arm 6 with the governor 13 to increase the speed of the latter, and incidentally the record plate, during the playing period of the record, to provide uniform speed of travel of the record sound groove past the stylus 8.

An acceptable form in which my invention may be carried into practice, may comprise a crank rod 14 keyed to the elbow of the tone arm 6 and extended vertically axially therethrough, the lower end of which is supported in the boss 15 on the sound box 10. A crank 16 is formed on this rod near its lower end. The upper end of said rod may be supported in the bracket 17 carried by the base plate 9, if required.

100 Connected to the crank aforesaid, and extended horizontally through the sound box 10, is a connecting rod 18, one end of which 110 is pivoted to the extremity of the rod 19, as at 20. This rod 19 extends through the

sound box 10 and longitudinally along the top thereof, being supported in the bearing 21. The other end of this rod is bent upwardly, and is connected as at 22 to the 5 governor speed controlling lever 23.

This governor speed controlling lever 23 is pivoted as at 24 to the end of the slide 25, which is slidably supported by the extension 26 on the motor base casting 27. 10 This slide is adjusted longitudinally by the adjusting arm 28, pivoted thereto as at 29 and fulcrumed to the extension 30 of the motor base casting 27, as at 31. The upper end of the adjusting arm extends through a 15 slot in the cabinet cover section 5.

In Fig. 1, I have shown the position of the components of the mechanism when the instrument is in starting position. In this position, the governor 13 is regulated for 20 slow speed. As a record is played, the tone arm 6 swings across the record toward its centre, which action gradually turns the rod 14 and moves the rod 19 in the direction indicated by the arrow *a* thus releasing the 25 governor from the position indicated by the line A—B, (Fig. 2) which indicates the starting position, and permitting the same to gradually accelerate the record plate and record to provide uniform speed of travel of 30 the record sound groove past the tone arm stylus. When the record has been fully played, the governor may have extended to the position indicated by the line C—D, dependent upon the size of the record. When 35 the motor 11 is stopped, the governor 11 recedes to the position shown in Fig. 1, permitting the tone arm to be swung across the record to starting position.

It is obviously necessary to provide a 40 speed control, to adjust the speed of the governor to accord with the various selections played. This is provided by mounting the lever 23 on the adjustable slide 25,

longitudinal adjustment of which shifts the lever 23 to any desired playing position, 45 such as exemplified in Fig. 3.

While the preferred embodiment of the invention has been described, it is to be understood that minor changes in the details of constructions, combination and arrangement of co-operating elements may be resorted to within the scope of what is claimed without departing from the spirit of the invention.

What I claim as new is:

1. In combination, record plate rotating means; a governor therefor; a speed control for said governor; a laterally swinging tone arm; a rod extending vertically through the pivotal axis of said tone arm and engaged to turn therewith; the lower end of said rod being bent in crank formation; a connecting rod reciprocally mounted and having one end connected to said control; a second connecting rod having one end pivotally connected to the first mentioned connecting rod and its other end connected to said crank formation. 60

2. In combination, record plate rotating means; a governor therefor; a speed control for said governor; a laterally swinging tone arm; a rod extending vertically through the pivotal axis of said tone arm and engaged to turn therewith; the lower end of said rod being bent in crank formation; a connecting rod reciprocally mounted and having one end connected to said control; a second connecting rod having one end pivotally connected to the first mentioned connecting rod and its other end connected to said crank 75 formation; said speed control being fulcrumed on a slide member and a means for reciprocating said slide member. 80

In testimony whereof, I affix my signature.

ALEXANDER ROY DAVIDSON.
